United States Patent Office

Des. 208,713
Patented Sept. 26, 1967

208,713

CASING FOR A TOY PHONOGRAPH

Karl A. Utrecht, Cincinnati, Ohio, assignor to Kenner Products Company, Cincinnati, Ohio, a corporation of Delaware

Filed May 25, 1966, Ser. No. 2,422

Term of patent 14 years

(Cl. D34—15)

Fig. 1

I claim:

The ornamental design for a casing for a toy phonograph, substantially as shown.
